DESCRIPTION

U.S. PATENT DOCUMENTS

FIG. 1 is a perspective view of an extrusion showing the
design.

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The extrusion is shown with a symbolic break in its length.
The appearance of any portion of the extrusion between the
break lines forms no part of the claimed design.
